FISH LURE

George H. Gowdy, St. Petersburg, Fla.

Application March 10, 1959, Serial No. 54,915

Term of patent 14 years

(Cl. D31—4)

Fig. 1

Fig. 2

Fig. 3

Figure 1 is a side view of a fish lure embodying my new design, the opposite side not shown being substantially like that shown, and

Figure 2 is an edge view thereof.

Fig. 3 is a cross-section through the body of the lure on the line 3—3 in Fig. 1, looking in the direction of the arrows.

In Figs. 1 and 3 the stippled shading represents contrasting color.

I claim:

The ornamental design for a fish lure, as shown and described.
